HENRY J. BLAKESLEE, OF MARLBORO, CONNECTICUT

THERMOSTAT

Application filed September 3, 1929. Serial No. 389,898.

This invention relates to a thermostat which is particularly adapted for controlling the action of heat regulating means but which is also very serviceable for use with other apparatus designed to be regulated according to temperature.

The object of the invention is the production of a thermostat which is cheap to manufacture, easy to adjust, and simple to set to obtain results at the desired temperatures.

The embodiment of the invention illustrated has a case enclosing in a strip of thermostatic responsive metal that has a normally fixed end electrically connected with a circuit terminal and a free end which projects between contacts that are electrically connected with other circuit terminals. The fixed end of the thermal strip is secured to a rotatably mounted axle to which is fastened an arm that extends to and is held by spring tension in engagement with a cam on a spindle that has a graduated disk or cylinder which projects through an opening in the casing cover. By turning the disk the free end may be adjusted between the contacts so that it will open and close the required circuits, as the temperature changes, in order to effect the desired action of the apparatus or means connected with the circuits.

In the accompanying drawings Fig. 1 shows a front view of the article. Fig. 2 is a plan with the casing cover removed. Fig. 3 is a side elevation with the cover in section. Fig. 4 is an end elevation with the cover in section.

The base 1 and the cover 2 may be made of any suitable insulating material. The cover may be omitted if desired. Extending upward from the base are walls 3 and 4 which are preferably formed integral with the base.

The inner end 5 of a coiled thermal strip 6 is secured to a metallic axle 7 which is rotatably supported by the walls 3 and 4. Fastened to the free end of the thermal strip shown is a finger 8, which extends between contacts 9 and 10, the former being threaded into the top of a post 11, and the latter being threaded into the conducting plate 12 that is fastened to the top of the wall 4. A circuit wire 13 may be electrically connected with

the post 11, and a circuit wire 14 may be electrically connected with the plate 12, preferably by means of a lead 15. A circuit wire 16 may be electrically connected with the axle 7 preferably by means of a lead 17.

Rotatably supported by the walls 3 and 4 is a spindle 18 fastened to which is a disk or cylinder 19 that is provided with suitable graduations and that in the preferred form extends outward through an opening in the casing cover. Secured to the spindle or to the disk is a cam 20. An arm 21 is fastened to the axle 7. This arm may be adjustably secured by means of a screw 22, and one end extends into engagement with the cam 20 while the other end is engaged by a spring 23 which holds the arm in engagement with the cam. When the arm is once adjusted by the makers of the device it requires no further attention.

By turning the disk the cam bearing upon the arm turns the axle to which the inner end of the coiled thermostatic strip is fastened. In use the disk, which extends through the cover and is the only active part that is exposed, is indexed to the desired degree of temperature to be retained, at which degree the finger will extend between but out of engagement with the circuit contacts 9 and 10. Upon a rise in temperature the action of the thermostatic strip causes the finger to engage with one circuit contact and upon a drop in temperature the strip causes the finger to return to neutral position or to engage the other circuit contact should the drop be sufficient.

This device is cheap to manufacture and is attractive in appearance, the only portion of the active mechanism shown being the graduated disk which is exposed through the opening in the cover and which is simple to turn with the thumb or finger for setting so that the device will act for the purpose of properly shifting the circuits to maintain the required temperature. With the thermo-responsive element mounted on an axis that is parallel to the plane of the base so said element has its movement perpendicular to the plane of the base, there is a saving of space which is advantageous when two or more are located side by side.

The invention claimed is:

1. A thermostat comprising a base and an enclosing casing, an axle rotatably mounted on the base and electrically connected with a circuit terminal, a coiled thermostatic strip having one end attached to said axle and its other end extending between circuit contacts, an arm adjustably fastened to said axle, a rotatably mounted graduated disk projecting through the casing, and a cam rotatable with said disk and engaging said arm, whereby the normal position of the thermostatic strip may be regulated by adjusting the arm with relation to the axle and the action of the thermostatic strip may be varied by rotating said disk and cam.
2. A thermostat comprising a base and an enclosing casing, an axle rotatably mounted transversely of the base, a coiled thermostatic strip having one end attached to said axle and its other end extending longitudinally of the base between circuit contacts, an arm adjustably fastened to and extending radially of said axle, a disk projecting through the casing and mounted to rotate on an axis transverse of the base, and a cam rotatable with said disk and engaging said arm, whereby the normal position of the thermostatic strip may be regulated by adjusting the arm with relation to said axle and the action of the thermostatic strip may be varied by rotating said disk and cam.
